George H. Curtis, Melrose, Mass., assignor to
Heinze Electric Corporation, Lowell, Mass., a
corporation of Michigan

Application February 21, 1940, Serial No. 90,405

Term of patent 7 years

To all whom it may concern:

Be it known that I, George H. Curtis, a citizen
of the United States and a resident of the city
of Melrose, in the county of Middlesex and State
of Massachusetts, have invented a new, original,
and ornamental Design for a Signal Horn Unit or
Similar Article, of which the following is a speci-
fication, reference being had to the accompany-
ing drawing, forming a part thereof.

On the drawing:

Figure 1 is a perspective view of a signal horn
unit, showing my new design.

Figure 2 is a side elevational view thereof.

I claim:

The ornamental design for a signal horn unit
or similar article, as shown.

GEORGE H. CURTIS.
